Primary Examiner — Eric Goodman*Assistant Examiner* — Amy Wierenga*(74) Attorney, Agent, or Firm* — Albert Bordas, P.A.(57) **CLAIM**

The ornamental design for a secure tablet kiosk enclosure, as shown and described.

DESCRIPTION

FIG. 1 is a top plan view of a secure tablet kiosk enclosure;
FIG. 2 is a front elevational view thereof;
FIG. 3 is a bottom view thereof;
FIG. 4 is a left elevational view thereof;
FIG. 5 is a rear elevational view thereof;
FIG. 6 is a right elevational view thereof;
FIG. 7 is a front isometric view thereof; and,
FIG. 8 is a rear isometric view thereof.

The broken lines are for environmental purposes only and form no part of the claimed design.

The present secure tablet kiosk enclosure is used to process credit cards.
